UNITED STATES PATENT OFFICE.

ZOE G. MAGNEA, OF NEW YORK, N. Y.

BOTTLE.

1,159,057.

Specification of Letters Patent.

Patented Nov. 2, 1915.

Application filed August 11, 1914, Serial No. 856,293. Renewed July 26, 1915. Serial No. 42,071.

To all whom it may concern:

Be it known that I, ZOE G. MAGNEA, a citizen of the United States, residing at New York, in the county of New York and State of New York, have invented new and useful Improvements in Bottles, of which the following is a specification.

An object of the invention is to provide a bottle of that class of bottles known as non-refillable bottles and which, when the original contents have once been withdrawn therefrom, will not be practicable for commercial usage and which, furthermore, will, after its original contents have been withdrawn, serve notice to the consumer, in the event it is refilled, that the bottle has been so refilled.

The invention contemplates, among other features, the provision of a bottle having therein suitable means which can be initially arranged in sealing position when the bottle is first filled and which must be released in order to extract the contents of the bottle and after being so released cannot be again brought into proper position to reseal the bottle if the same be subsequently refilled.

In the further disclosure of the invention, reference is to be had to the accompanying drawings, constituting a part of this specification, in which similar characters of reference denote corresponding parts in all the views, and in which:

Figure 1 is a vertical sectional view taken through the bottle, showing the neck thereof open and unsealed; Fig. 2 is a similar view showing the neck sealed; Fig. 3 is a similar view after the wires or securing members have been cut and the contents of the bottle removed; and Fig. 4 is a fragmentary perspective view showing the manner of securing the members or wires around the neck of the bottle.

Referring more particularly to the views, I provide a bottle body 10 having an integral neck 11 provided with an annular groove 12, a plurality of diametrically opposed apertured guide lugs 13 being formed with the interior of the neck 11, as shown. Secured to a lug 14 on the bottom 15 of the bottle body 10 is a contractile helical spring 16, to the free end of which is suitably secured a preferably concaved sealing member 17 of greater diameter than the neck 11, said sealing member having attached there-

to the lower ends of suitable securing members 18 in the nature of flexible wires and which pass upwardly through the apertured lugs 13 and are adapted to project exteriorly of the bottle body 10. 55

When the sealing member 17 is in the position shown in Fig. 1 the bottle is in condition for filling and when the same has been initially filled with the desired fluid, an upward pull is exerted on the securing members 18, thus moving the sealing member 17 60 upwardly against the contractile action of the spring 16, to seal the inner end of the neck 11, said securing members being bent around the upper end of the neck and twisted around the neck in the annular 65 groove 12, as shown in Figs. 2 and 4. If desirable, a suitable cork 19 can be inserted in the neck as shown, said cork being held in position by the securing members 18, which, due to the softness and pliability of 70 the cork, will press into the periphery thereof. 75

Now when it is desired to remove the contents of the bottle, the securing members 18 are cut at the point where they project from 80 the neck, thus releasing the spring 16 and causing the same to contract, thereby removing the sealing member 17 from its sealed position and causing the same to fall to the bottom of the bottle. The bottle will 85 now be opened and the contents can be readily poured therefrom, and it will be clearly seen that the bottle cannot be conveniently refilled for the reason that the short or cut securing members 18 will lie 90 wholly within the bottle and, furthermore, could not be readily arranged in position to secure the sealing member in sealing position or account of their shortness. 95

With a bottle of the character described it will be clearly apparent that when the bottle has been once used and the original contents extracted therefrom, it cannot be conveniently reused for the reason that the sealing member lies in the bottom of the 100 bottle and will give notice to the public or consumer that the bottle as initially packed and sold must have been previously opened and its contents extracted, diluted or replaced by an inferior fluid. 105

The sealing member may be made of porcelain, wood, rubber or any other desirable material and, particularly when made of a

slightly resilient material, will effectively seal the inner end of the neck when the member is in the position shown in Fig. 2.

Having thus described my invention, I 5 claim:

1. In a bottle, the combination with a bottle body having a neck provided with an annular groove, a plurality of apertured lugs projecting from the inner face of the neck, 10 a lug in the bottom of the bottle body, a contractile spring having one end thereof secured to the lug in the bottom of the bottle body, a sealing member carried on the other end of the spring, and wire-like securing members having their inner ends connected with the sealing member and passing through the apertured lugs on the neck, said securing members being adapted to project exteriorly of the neck and be twisted around 15 the neck in the annular groove thereof and secure the sealing member in position to seal the inner end of the neck.
2. In a bottle, a bottle body having a neck, a sealing member for sealing the inner end of the neck, a contractile spring secured 20
- 25

in the bottle body and connecting with the sealing member, and wire-like securing members connecting with the sealing member and holding the same in sealing position and against the action of said spring, said securing members passing exteriorly of the bottle. 30

3. In a bottle, a bottle body having a neck, a sealing member for sealing the inner end of the neck, a contractile spring secured in the bottle body and connecting with the sealing member, wire-like securing members connecting with the sealing member and holding the same in sealing position and against the action of said spring, said securing members passing exteriorly of the bottle, 35 and guide lugs in the neck of the bottle body and having the securing members passing therethrough. 40

In testimony whereof I affix my signature in presence of two witnesses.

ZOE G. MAGNEA.
